CLARENCE A. BATES, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

BRIDGING DEVICE FOR FUSE-RECEPTACLES.

1,252,219.

Specification of Letters Patent.

Patented Jan. 1, 1918.

Application filed January 21, 1916. Serial No. 73,432.

To all whom it may concern:

Be it known that I, CLARENCE A. BATES, a citizen of the United States of America, and residing at Bridgeport, in the county of 5 Fairfield and State of Connecticut, have invented a certain new and Improved Bridging Device for Fuse-Receptacles, of which the following is a specification.

My invention relates to a bridging device 10 for fuse receptacles and the object of my invention is to provide a simple and inexpensive fitting which may be applied to standard fuse receptacles to bridge the contacts of the latter and establish a full capacity connection between the same in place of the ordinary fuse of limited capacity.

In the accompanying drawings,

Figure 1 is a perspective of a cut-out block with associated fuse plug and bridging device in position to be inserted;

Fig. 2 is a plan of said block;

Fig. 3 is a section through one of the receptacles of the block with the bridge piece inserted and partially broken away;

Fig. 4 is an enlarged section similar to Fig. 3;

Fig. 5 is an inverted plan of the body of the bridging piece; and

Fig. 6 is a dropped perspective of the parts 30 of the latter.

It has been a common practice in wiring installations to provide a grounded connection to protect the system from the dangers of an overloaded circuit. This grounded connection has in most cases been established through a fused line. The practice of using a fuse in the grounded line has been disapproved by the National Board of Fire Underwriters with the result that a change in 35 existing installations has been required to eliminate the fuse in the ground line. Where the multiple fuse blocks have been used, compliance with the Underwriters' regulation has necessitated either the discarding 40 of the multiple fuse block in the grounded connection, or a make-shift device between the contacts of the fuse block.

The present invention provides a simple and inexpensive bridging device which may 50 be inserted in any fuse block to afford a workmanlike bridge of full capacity between the contacts of the receptacle.

Referring to the accompanying drawings, a multiple fuse block 10 of common type is 55 here shown comprising a block of insula-

tion having mounted thereon a pair of plug receptacles 11 and 12 with usual wire terminals 13, 14, 15 and 16. The wire terminals 13 and 14 take the current to the shell contacts 17 and 18, while the terminals 15 and 16 are connected to the center contacts 19. and 20 respectively. An ordinary fuse plug 21 is shown above the receptacle 11 for insertion therein, the circuit completed there-through being led as usual to a lighting or 60 other system, as may be desired. The present bridging device is shown in position to be inserted in the receptacle 12.

The bridging device 22 just referred to comprises, in the form here shown, a block 70 23 of insulation the entering end of which is embraced by a combined shell screw 24 and center contact 25 formed from a single integral sheet of copper. The upper edge of the sheet is spun over the upper face of the 75 block 23 at 26 to rigidly assemble these parts. In order to prevent swiveling of the shell on the block, a pair of studs 27 and 28 are pressed inward from the entering end of the shell to engage in corresponding wells 29 80 and 30 formed in the lower face of the block. A thread 31 of standard pitch is formed on the shell to engage the thread of the receptacle shell contact 17. A transverse groove 32 formed in the upper face of the 85 porcelain block 23 is of proper dimensions to receive the end of a screw-driver, thus enabling the wireman to readily insert the bridging device and screw the same fully home in the receptacle, without danger to 90 himself, since the screw-driver does not come in contact with the contacts of the device.

It is obvious that when the present bridging device is inserted it forms a connector of full capacity between the shell 17 and center 95 contact 19 of the receptacle 12, thus giving an uninterrupted connection through the fuse plug receptacle to the ground. While this connection is sufficient to enable the lineman to meet the Underwriters' requirement, it would be possible to remove the device and again reinsert a fuse plug, unless some means are provided for permanently securing the device in its inserted position. To afford means for preventing such a removal, I have associated with the device a small piece of readily fusible solder, here in the form of a stick 33, the lower end of which enters a bay 34 formed in the porcelain body 23 in register with a hole 35 in the 100 105 110

shell 24. This block of solder may take the form of a small stick or wire of solder the lower end of which may be enlarged to form a head which is engaged by the rolled over edge 26 of the shell, thus preventing its accidental loss before it has been utilized. After the device has been inserted and screwed home, it is only necessary to apply a hot soldering iron to the exposed portion of the 10 solder wire 33 to melt the latter so that it runs down and escapes through the hole 35 in the shell, soldering the latter to the screw shell 17 of the receptacle. Of course it is possible to pour a drop or two of solder into 15 the well 34 in case the stick 33 has been lost, thus accomplishing the same result. It is now practically impossible to remove the bridging device from the receptacle.

The present device affords, as will be seen, 20 a simple and inexpensive fitting which may be readily installed and permanently secured in the receptacle in place of the fuse plug without injury to either and without changing the installation otherwise than by 25 the removal of the fuse plug and the substitution therefor of the present bridging device. This is a matter of only two minutes' work and of practically negligible expense.

While I have illustrated my invention in a 30 form which is commercially practicable and economical, various modifications of construction will readily occur to those skilled in the art without departing from what I claim as my invention. In the following 35 claims I use the term "full capacity" in the sense of a conductor having a current-carrying capacity substantially equal to that of the line in which it is inserted, even under abnormal load.

40 I claim as my invention:—

1. A bridging device for fuse receptacles, comprising a plug having a full capacity connection between the shell and center contacts thereof and means for permanently securing 45 said plug in inserted position.

2. A bridging device for fuse receptacles, comprising an insulating body and contacts thereon adapted to engage the receptacle contacts and establish a full capacity connection between the latter and means for 50 permanently securing said plug in inserted position.

3. A bridging device comprising an insulating body having integral shell and center 55 contacts thereon and a block of solder carried by said insulating body in position to solder on melting the shell contacts of said bridging device and receptacle.

4. A bridging device comprising a block 60 of insulation, a shell contact mounted there-

on and a supply of solder carried by said insulating body, said shell being perforated to permit the flow of said solder on melting into the space between said shell and the shell of the receptacle.

5. A bridging device comprising an insulating body, a shell and center contact mounted thereon and having a full capacity connection between the same, together with a supply of solder carried by said device in 70 position to flow between one of said contacts and a receptacle contact upon melting after the device has been installed.

6. A bridging device comprising an insulating body, a shell contact thereon, the latter being apertured to permit the flow of solder therethrough into the space between the same and the receptacle shell contact to rigidly secure said device in inserted position.

7. A bridging device for plug receptacles comprising a plug having integral shell and center contacts and means for permanently securing said shell in inserted position in a receptacle.

8. A bridging device for plug receptacles comprising a button of insulating material having its outer margin offset to form a ledge in combination with integral screw shell and center contacts surrounding said button, the outer margin of said screw shell engaging said ledge to secure said parts in assembled position.

9. A bridging device for plug receptacles comprising a button of insulating material 95 having its outer margin offset to form a ledge in combination with integral screw shell and center contacts surrounding said button, the outer margin of said screw shell engaging said ledge to secure said parts in 100 assembled position, together with means to prevent relative rotation of said screw shell and insulating button.

10. A bridging device for plug receptacles comprising a button of insulating material 105 recessed at its outer margin to form a soldering well, together with a screw shell surrounding said button and apertured in register with said well to permit the flow of solder therethrough to the shell contact of a 110 coöperating receptacle, for the purpose described.

In testimony whereof I have signed my name to this specification, in the presence of two subscribing witnesses.

CLARENCE A. BATES.
